LUBRICANT PUMP STRUCTURE

Eupert P. Esser, Bryan, Ohio, assignor to The
Arc Equipment Corporation, Bryan, Ohio, a
corporation of Ohio

Application March 21, 1935, Serial No. 12,197

30 Claims. (Cl. 221—1)

The object of my invention is to provide a lubricant pump structure, which is simple, durable and comparatively inexpensive to manufacture.

5 A further object is to provide a lubricant pump structure adapted for delivery of lubricant at either a high pressure or a low pressure as desired, a single adjustment being necessary for changing from one to the other.

10 Still a further object is to provide a novel operating means for a high and low pressure lubricant pump, wherein the low pressure pump supplies lubricant to the high pressure pump in such a manner that a minimum of compressed air is used for either low or high pressure operation.

15 Still another object is to provide low and high pressure pistons so associated with each other that the high pressure piston drives the low pressure piston in one direction and the low pressure piston drives the high pressure piston in the opposite direction when lubricant is being discharged at low pressure, while when lubricant is being discharged at high pressure, the high pressure piston is driven by the lubricant pumped by the 20 low pressure piston rather than directly by the low pressure piston itself.

25 Still a further object is to so associate a control valve with the two pistons that it serves for both during either high pressure or low pressure operation of the pump structure.

30 Still another object is to provide a check valve connection between the low pressure and high pressure pumps, which is selectively renderable operative or inoperative, so that high pressure or low pressure dispensation of lubricant respectively can be accomplished.

35 Still another object is to provide a novel type of relief valve to prevent undue pressure in the low pressure pump, this valve being so arranged 40 that it is responsive to lubricant pressure in proportion to the pressure of the actuating fluid for the pump structure.

45 Still another object is to provide a unitary pump structure which can be supported on a barrel or other lubricant container, and thus is adaptable for removing lubricant from the container in which the lubricant is shipped, the unit being readily removable and placeable on another container when the first one is emptied.

50 Another object is to provide one form of the invention in which the low pressure pump only operates the high pressure pump in one direction, compressed air being used to operate the high pressure pump in the other direction.

55 Still another object is to provide in this form

of the invention a pair of control valves, one for the low pressure pump and the other for the high pressure pump, and a manually settable selector for selecting either high pressure or low pressure dispensation from a single nozzle.

5 Another object is to provide an encasing member for a drum of lubricant having the pump structure mounted on it in such manner that this casing together with the entire pump unit permanently attached thereto can be removed from a drum of lubricant and set on the floor without getting dirt into the intake of the pump.

Still another object is to provide a casing and pump secured together as a unit and positionable over a wheeled platform for supporting a container of lubricant, the wheels being within the outline of the casing, so that a minimum of floor space is required for the unit.

With these and other objects in view, my invention consists in the construction, arrangement 20 and combination of the various parts of my lubricant pump structure, whereby the objects contemplated are attained, as hereinafter more fully set forth, pointed out in my claims, and illustrated in the accompanying drawings, in which:

25 Figure 1 is a side elevation, mostly in section, of a lubricant pump structure embodying my invention and showing it associated with a lubricant barrel, a high pressure lubricant line and control valve being illustrated in connection therewith.

30 Figure 2 is a sectional view on the line 2—2 of Figure 1.

35 Figure 3 is a sectional view on the line 3—3 of Figure 1, and showing a low pressure delivery hose and control valve associated therewith.

Figure 4 is an enlarged sectional view on the line 4—4 of Figure 2.

40 Figure 5 is a side elevation of another form of the invention utilizing a single dispensing hose instead of one for low pressure and one for high pressure.

45 Figures 6 and 7 are enlarged, sectional views on the lines 6—6 and 7—7 of Figure 5.

Figure 6A is a sectional view on the line 6A—6A of Figure 6, showing a selector control in another 45 position.

50 Figure 8 is a sectional view on the line 8—8 of Figure 6, showing the control valves for the low and high pressure pumps.

Figure 9 is a sectional view on the line 9—9 of 50 Figure 6; and

Figure 10 is a sectional view on the line 10—10 of Figure 9.

In the accompanying drawings, I have used 55

- the reference numeral 10 to indicate a container for lubricant or the like, which is usually in the form of an oil barrel. The upper end thereof is open, the container being shown with a neck 12, although my device may be used with a barrel having an opening of but slightly larger diameter than a foot valve fitting shown at 14. The foot valve fitting 14 is mounted on the lower end of a low pressure cylinder 16.
- 10 Within the cylinder 16, a piston rod 18 is arranged, having secured to the lower end thereof a piston consisting of parts 20, 22 and 24. The part 20 is a washer-like element secured to the lower end of the rod 18 and the part 22 is 15 also a washer-like element secured by a cap screw 26 to the element 20 with the element 24 (a cup leather) interposed between them. The elements 20 and 22 are perforated and a check valve disc 28 rests against the upper face of the element 20, it being retained thereagainst by a spring 30.
- The foot valve fitting 14 has therein an intake check valve 32, the disc 28 being a discharge check valve.
- 25 From the description of the parts thus far made, it is obvious that vertical reciprocation of the piston with its cup leather 24 in the cylinder 16 will upon the down stroke cause the valve 28 to open, and upon the up stroke cause the valve 32 to open, whereby upon a plurality of reciprocations, lubricant is caused to rise in the cylinder 16.
- The rising lubricant enters a passageway 34 from which it flows into a bore 36. From the 35 bore 36, it flows through perforations 38 of a sleeve 40 and into a bore 42 of the sleeve.
- A low pressure hose 44 is connected with the sleeve 40 and terminates in a control valve 46 and a discharge nozzle 48.
- 40 A check valve 50 is associated with the sleeve 40 and normally retained seated by a spring 52. The spring 52 and the check valve 50 are rendered operative in the position shown in Figure 3, although they can be rendered inoperative by unscrewing a screw 54 to the inner end of which a plug 56 is secured. When this plug is turned outwardly, so that it seats against the inner end of a closure nut 58, the check valve 50 can no longer function.
- 45 The discharge side of the check valve 50 is connected by a passageway 60 to a high pressure cylinder 62. A high pressure plunger 64 is reciprocable therein.
- The high pressure cylinder 62 has a discharge 55 passageway 66 connected with a discharge fitting 68.
- A ball check valve 70 is arranged in the fitting 68 and serves as an outlet check valve for the high pressure lubricant from the cylinder 62.
- 60 A swivel fitting 72 is connected with the fitting 68 and by a high pressure hose 74 with a control valve 76. The control valve has a discharge fitting 78 for connection with lubricant reception fittings of an automobile or the like.
- 65 For operating the piston rod 18 and the plunger 64, I provide pistons 80 and 82 reciprocable in cylinders 84 and 86.
- The piston 80 is adapted for constant air pressure on the under surface thereof from a supply pipe 88 connected with a chamber 90, which in turn communicates with the lower end of the cylinder 84.
- The lower end of the cylinder 86 is open to atmosphere through a chamber 92 in a base member 94 of the cylinders 84 and 86. This base

member is mounted on a base plate 96, which is supported on the barrel or other container 10.

The cylinders 84 and 86 are provided with suitable cylinder heads 98 and 100, while the pistons 80 and 82 are provided with piston rods 102 and 104.

A control valve is provided for admitting compressed air to the upper ends of the cylinders 84 and 86 and exhausting air therefrom. It is shown best in Figure 4 and comprises an intake 10 valve seat 106, an outlet valve seat 108 in the form of a washer of fiber or the like, and a valve plug 110. The valve plug 110 has an intake end 112, engageable with the seat 106, and an exhaust end 114 engageable with the seat 108.

Compressed air is supplied from the chamber 90 through a pipe 116 to the valve seat 106. Air is exhausted from the valve seat 108, through exhaust ports 118. The control valve body (between the seats 106 and 108) is connected by 20 passageways 120 with hollow mounting bolts 122, which in turn communicate with passageways 124 leading to the upper ends of the cylinders 84 and 86.

The valve plug 110 is operable to its opposite 25 positions by a snap acting toggle lever 126, with which an over-center spring 128 is associated. The toggle lever 126 is initially moved by either a shoulder 130 or a shoulder 132 of a valve rod 134. The rod 134 is connected with a cross piece 136 30 having one end rigidly connected with the piston rod 104 as by being confined between a shoulder 138 and a lock nut 140. Its opposite end is freely movable along the rod 102, the rod having a shoulder 142 to limit its movement in one direction relative thereto.

In Figures 6 to 10, I show a modified construction in which there is a foot valve 154 on the lower end of a low pressure grease cylinder 156. A piston 158 is reciprocably mounted within a 40 cylinder 160 and is connected by a plunger 162 and a stem 164 with a low pressure grease piston 166. A check valve 168 is mounted in the piston 166.

Air and grease packings 170 and 172 are provided for the cylinder 156. Compressed air constantly acts on the under side of the piston 158, it being introduced through a supply pipe 174 into a chamber 176.

A high pressure pump is provided in the form 50 of a cylinder 194 and a plunger 196. The cylinder 194 communicates by means of passageways 198 and 200 with the low-pressure cylinder 156 (see Figure 10). A check valve 202 is interposed between a hollow fitting 204 and the high pressure cylinder 194, the check valve 202 seating against its inner end. The interior of the fitting 204 communicates by means of an opening 206 with the passageway 200.

An outlet check valve 208 (see Figure 9) communicates with the cylinder 194 and a lubricant delivery hose 210 is connected therewith, a nozzle being mounted on the outer end of the hose as shown for instance in Figure 1.

For reciprocating the plunger 196, I provide a 55 piston 212 reciprocable in a cylinder 214.

Communicating with the chamber 176 is a hollow cap screw 178 for retaining a control valve body 180 in position as shown in Figure 6. A second cap screw 182 is also used for retaining the valve body 180 in position. The hollow cap screw 178 affords communication between the chamber 176 and a valve seat 184 in the valve body 180. A valve member 186 is adapted for seating against the seat 184 and when unseated 70

therefrom as shown in Figure 6 permits the compressed air to flow through a passageway 188 and a tubular rod 190 to a normally closed control valve 192.

5 For opening the valve 192, I provide a cam disc 216 pivoted on a sleeve 218 held in position under a nut 220 on a tie rod 222. The cam disc 216 has a wing-like handle 224 and a depression shown at 226 to receive a pin 228 when the depression registers therewith. The pin 228 when pressed downwardly opens the valve 192 and is sealed relative thereto by a flexible diaphragm 230.

15 As shown in Figure 6A when the wing 224 is swung in either direction from a central position where the depression 226 does not register with the pin 228, the pin will be depressed for opening the valve. Instead of the construction just described, the wing 224 may have but two positions, 20 the left position for instance with the valve 192 closed and the right position causing the valve to be open for high pressure operation.

25 When the valve 192 is open, air can flow from the tubular rod 190 through a passageway 232 to the upper end of the cylinder 214. The valve member 188 when unseated from the seat 184 is seated against a seat 234 of suitable material, and when unseated from this seat and seated against the seat 184, air can flow from the cylinder 214 through the parts 232, 192, 190 and 188, past the seat 234 to atmosphere through passages 236, for thus exhausting the air from the cylinder 214. The valve plug 186 is operated to its opposite positions by a toggle lever 238, which in turn is operated by shoulders 240 and 242 of a reciprocable rod 244. The rod 244 is connected with the piston 212 (see Figure 8).

35 The parts 178 to 190 and 234 to 244 are for the high pressure pump. Similar parts are provided for the low pressure pump and are given the same reference numerals with the addition of "a".

40 As shown in Figure 7, the tubular rod 190a communicates directly through a passageway 246 with the cylinder 160. Since the lower side of the piston 158 is subjected to air pressure, I provide a seal as at 248 to prevent leakage around the rod 246a.

50 *Practical operation for low pressure delivery of grease*

45 Referring to Figures 1 to 4, at low pressure, the screw 54 is turned outwardly until the check valve 50 is rendered inoperative. When the low pressure control valve 46 is opened, the control valve 110 being in the position shown in Figure 4 will admit air to the upper ends of the cylinders 84 and 86. This air in the cylinder 84 will counter-balance the air in the chamber 90, while in the cylinder 86, it will force the piston 82 and the plunger 64 downwardly. This will tend to pump grease through the cylinder 62 past the check valve 50 and into the hose 44, until the arm 136 engages the shoulder 142, whereafter the piston 88 and the low pressure piston 24 will be driven downwardly.

55 At the lower end of the stroke, the position of the valve 110 will change, whereupon air is exhausted from the upper ends of the cylinders 84 and 86, and the air pressure in the chamber 90 will then raise the piston 80 and through the cross bar 136 the piston 82. This will cause the low pressure pump piston 24 to pump grease into the hose 44.

At the upper end of the stroke, the position of the valve 110 will again change and as long as the valve 46 is held open, simultaneous reciprocation of the pistons will continue.

60 Referring to Figures 6 to 10, air pressure within the chamber 176 tends constantly to raise the piston 158 for drawing grease in through the foot valve 154.

For low pressure operation, the wing 224 is adjusted to the position shown in Figure 6, so that air can not flow past the valve 192 into the high pressure pump cylinder.

65 When flow of grease is permitted by opening the nozzle on the outer end of the hose 210 and the valve of the valve body 180a is in the position 15 of Figure 6, air will flow from the chamber 176 through the cap screw 178a and through the control valve (designated generally as V in Figure 8) through the tubular rod 190a to the upper 20 end of the cylinder 160.

This will cause the piston 158 to move downwardly since its top area is greater than the effective area of its lower side, because of the plunger 162. This will open the valve 168, permitting the piston 158 to move downwardly 25 through the grease in the cylinder 156, the foot valve 154 also being closed. At the lower end of the stroke, the position of the valve V will be changed through the rod 244a and the toggle lever mechanism 238a, so that the air will be exhausted from the cylinder 160 to atmosphere 30 through the ports 236a.

70 Reciprocation of the low pressure pump piston 158 will continue until the nozzle on the end of the hose 210 is closed, whereupon the back pressure 35 will stop operation of the low pressure pump. During low pressure operation, the plunger 162 is held in its upper position by lubricant in the cylinder 156, so that the plunger does not interfere with the lubricant flowing at low pressure 40 through the cylinder.

75 During reciprocation, displacement of air between the packings 170 and 172 is taken care of by a passageway 250 shown in Figure 10 and indicated by dotted lines in Figure 9. This passageway communicates at its lower end with the atmospheric space within a chamber 252 depending from the base of the cylinders 160 and 214.

80 *Practical operation for high pressure delivery of grease*

85 Referring to Figures 1 to 4, the check valve 50 is adjusted to the position of Figure 3 and the control valve 76 is used.

90 Assuming the parts to be in the positions shown in Figures 1, 2 and 4, when the valve 76 is opened, the compressed air in the upper ends of the cylinder 86 will cause the plunger 64 to move downwardly to dispense lubricant at high pressure 60 through the check valve 76 and into the hose 74.

95 When the cross arm 136 engages the shoulder 142 of the piston rod 102 in addition to pumping the lubricant out at high pressure, the pump piston 24 will be driven downwardly for intake of lubricant into the cylinder 16 above the piston 24.

100 When the position of the valve 110 changes, air pressure in the chamber 90 will raise the pump piston 24 for causing upward flow of lubricant in 70 the cylinder 16 and through the check valve 50 into the high pressure cylinder 82.

105 Since the area of the piston 24 is greater than that of the plunger 64, the plunger will be driven upwardly by the lubricant at a greater speed than 75

the piston 24, causing the arm 136 to leave the shoulder 142, as shown in Figure 1. Accordingly after but a short up stroke of the piston 80, the piston 82 will have completed its up stroke for changing the position of the valve 110 and thus repeating the cycle.

It is therefore obvious that by using the low pressure pump to actuate the high pressure pump on its intake stroke, less air is required than if the piston 80 were operated at full stroke.

In the event that during high pressure delivery, foreign matter gets under the check valve 50, there will be danger of the high pressure lubricant acting upon the low pressure hose 44 and damaging it. To take care of such a contingency, I have provided a relief valve shown in Figure 3, having a cup leather 144, responsive to the pressure in the chamber 90, and a plunger pin 146 responsive to the pressure in the passageway 34.

20 A passageway 148 is provided for this purpose.

Whenever the pressure of the grease exceeds a certain proportional relation to the pressure of the compressed air, the plunger 146 will be driven inwardly far enough to permit the excess lubricant to pass through ports 150 into the space in the base 94 and fall back into the container 10.

By utilizing air pressure to constrain the relief valve toward closed position instead of a spring, the relief pressure of the lubricant is in exact proportion to the pressure of the actuating fluid.

Referring to Figures 6 to 10 for high pressure operation, the wing 224 is turned so that the cam 216 depresses the pin 228 for opening the valve 192 as in Figure 6A.

25 With the valve plug 186 in the position shown in Figure 6, air will be admitted through the valve 192 to the cylinder 214 above the piston 212. This will lower the plunger 196 for closing the check valve 202 and opening the check valve 208 and forcing the lubricant through the hose 210 through the nozzle at high pressure whenever the nozzle is opened.

At the lower end of the stroke of the piston 212, the high pressure control valve (indicated generally by the reference character V' in Figure 8) will be changed in position so as to exhaust the air from the cylinder 214. The low pressure piston 166 can then move upwardly for forcing another charge of lubricant through the check valve 202 into the cylinder 194 and thereby causing the plunger 196 to move upwardly at a more rapid rate than the movement of the piston 166 because of the relative areas. For instance the piston 166 might move about $\frac{1}{6}$ th of its stroke for effecting a full stroke upward movement of the plunger 196.

60 When the piston 212 reaches its upward limit of movement the valve V' will again be changed in position for starting the down stroke, and this cycle will be repeated a number of times, while the piston 166 is moving upwardly. When the piston 166 finally reaches its upward limit of movement, it will again move downwardly and then move up again in steps as long as the high pressure pump is being used.

65 In the event that there are air pockets in the grease, these can be taken care of through a relief valve 152 shown in Figure 1 or a similar valve 152 shown in Figure 9.

In Figure 9, I have shown the passageway 254 through which the grease can flow after the air pocket has been eliminated back into the chamber 252 and find its way back into the grease

drum 10a, instead of being discharged to atmosphere as in Figure 1.

After the air pockets are eliminated, the pump is properly primed, so that it can work in the manner intended for either low or high pressure dispensation of lubricant.

The pump shown in Figures 6 to 10 is mounted on a flared base member 256 secured to the upper end of an encasing member 258. The member 258 is preferably mounted on a wheeled platform 260 having castor wheels 262 for convenience in wheeling the pump structure from one position to another about the service station.

10 Lugs 264 serve to limit the downward movement of the casing 258 relative to the platform 260 for predetermining the position of the foot valve 154 relative to the bottom of the drum 10a which rests on the platform.

15 Also the lower end of the casing 258 is considerably below the foot valve 154, so that when the casing is removed from its position surrounding the grease drum and set on the floor, dirt and other foreign matter from the floor does not get into the foot valve.

20 Suitable latches of the leaf spring type shown at 266 can be provided, if found necessary, to prevent undesired disconnection of the casing 258 from the platform 260. These are conveniently retracted by knobs 268 when it is desired to remove the casing 258 from the platform 260.

25 The wheels 262, it will be noted, are within the outline of the casing 258. This makes a unit, the outline of which is defined by the casing and the casing is preferably of square shape 35 with rounded corners, so that a minimum of floor space must be provided for a plurality of lubricant pump structures. This makes it possible for a plurality of the casings to be positioned compactly along the wall in a service station without taking up prohibitive floor space, and such an arrangement presents a very neat appearance for the station.

30 Changes may be made in the construction and arrangement of the various parts of my lubricant pump structure, without departing from the real spirit and purpose of my invention, and it is my intention to cover by my claims, any modified forms of structure or use of mechanical equivalents, which may be reasonably included 40 within their scope.

45 I claim as my invention:

1. In a lubricant pump structure, a low pressure high volume pump, a high pressure low volume pump receiving lubricant from said low pressure pump, a first power piston connected with said low pressure pump for discharging lubricant therefrom, a second power piston connected with said high pressure pump for discharging lubricant therefrom and an operative connection between said pistons, whereby each will cause intake of lubricant into the pump of the other piston.

50 2. In a lubricant pump structure, a low pressure high volume pump, a high pressure low volume pump receiving lubricant from said low pressure pump, a first power piston connected with said low pressure pump for discharging lubricant therefrom, a second power piston connected with said high pressure pump for discharging lubricant therefrom and a lost motion operative connection between said pistons, whereby each will cause intake of lubricant into the pump of the other piston, and lubricant from said low pressure pump can act upon said high pressure 70

pump to cause movement of said second piston independent of said first piston, such movement being permitted by said lost motion connection.

3. In a lubricant pump structure, a low pressure high volume pump, a high pressure low volume pump receiving lubricant from said low pressure pump, a first power piston connected with said low pressure pump for discharging lubricant therefrom, a second power piston connected with said high pressure pump for discharging lubricant therefrom, an operative connection between said pistons, whereby each will cause intake of lubricant into the pump of the other piston, and a check valve between said low and high pressure pumps and opening toward the high pressure one.

4. In a lubricant pump structure, a low pressure high volume pump, a high pressure low volume pump receiving lubricant from said low pressure pump, a first power piston connected with said low pressure pump for discharging lubricant therefrom, a second power piston connected with said high pressure pump for discharging lubricant therefrom, a lost motion operative connection between said pistons, whereby each will cause intake of lubricant into the pump of the other piston and lubricant from said low pressure pump can act upon said high pressure pump to cause movement of said second piston independent of said first piston, such movement being permitted by said lost motion connection, a check valve between said low and high pressure pumps and opening toward the high pressure one, and means for selectively rendering said check valve operable for high pressure delivery of lubricant from said high pressure pump or inoperative, for low pressure delivery of lubricant from said low pressure pump.

5. In a lubricant pump structure, a low pressure high volume pump, a high pressure low volume pump receiving lubricant from said low pressure pump, a first power piston connected with said low pressure pump for discharging lubricant therefrom, a second power piston connected with said high pressure pump for discharging lubricant therefrom, an operative connection between said pistons, whereby each will cause intake of lubricant into the pump of the other piston, and an actuating fluid valve for admitting actuating fluid to and exhausting it from said pistons.

6. In a lubricant pump structure, a low pressure high volume pump, a high pressure low volume pump receiving lubricant from said low pressure pump, a first power piston connected with said low pressure pump for discharging lubricant therefrom, a second power piston connected with said high pressure pump for discharging lubricant therefrom, a lost motion operative connection between said pistons, whereby each will cause intake of lubricant into the pump of the other piston, and lubricant from said low pressure pump can act upon said high pressure pump to cause movement of said second piston independent of said first piston, such movement being permitted by said lost motion connection, and an actuating fluid valve for admitting actuating fluid to and exhausting it from said pistons.

7. In a lubricant pump structure, a low pressure high volume pump, a high pressure low volume pump receiving lubricant from said low pressure pump, a first power piston connected with said low pressure pump for discharging lubricant therefrom, a second power piston connected with said high pressure pump for discharging lubricant

therefrom, fluid pressure tending constantly to reciprocate said first piston, said low pressure pump being associated with said high pressure pump so that lubricant from said low pressure pump can act upon said high pressure pump to cause movement of said second piston in one direction, fluid pressure for moving said second piston in the opposite direction, and means for selectively rendering said high pressure pump responsive or non-responsive to said fluid pressure, said low pressure high volume pump delivering low pressure high volume lubricant when said means renders said high pressure pump non-responsive.

8. In a lubricant pump structure, a low pressure high volume pump, a high pressure low volume pump receiving lubricant from said low pressure pump, a first power piston connected with said low pressure pump for discharging lubricant therefrom, a second power piston connected with said high pressure pump for discharging lubricant therefrom, an operative connection between said pistons, whereby each will cause intake of lubricant into the pump of the other piston, actuating fluid acting constantly on said first piston in a discharging direction, and an actuating fluid control valve for admitting actuating fluid to counterbalance said constantly acting fluid pressure to permit the second piston to move in a direction for intake of lubricant into said high volume pump, said valve being operable to also exhaust fluid from said first piston and simultaneously therewith exhaust actuating fluid from said second piston and to introduce actuating fluid thereto to move it in a direction for discharge of lubricant from said low volume pump when actuating fluid is being introduced to said first piston.

9. In a lubricant pump structure, low and high pressure pumps, said high pressure pump receiving lubricant from said low pressure pump, a first means for operating said low pressure pump, a second means for operating said high pressure pump, a controller for said first and second means, said controller being operable by movement of the second means, an operative but lost motion connection between said first and second means, low pressure lubricant flowing from said low pressure pump acting upon said high pressure pump to cause movement thereof at a greater speed than said first means, said lost motion connection permitting such movement.

10. In a lubricant pump structure, low and high pressure pumps, said high pressure pump receiving lubricant from said low pressure pump, a first means for operating said low pressure pump, a second means for operating said high pressure pump, a controller for first and second means, said controller operated by movement of the second means, an operative but lost motion connection between said first and second means, low pressure lubricant flowing from said low pressure pump acting upon said high pressure pump to cause movement thereof at a greater speed than said first means, said lost motion connection permitting such movement, and a check valve between said low and high pressure pumps and opening toward the high pressure one.

11. In a lubricant pump structure, low and high pressure pumps, said high pressure pump receiving lubricant from said low pressure pump, a first means for operating said low pressure pump, a second means for operating said high pressure pump, a controller for said means, said controller being responsive to movement of the

- second means, an operative but lost motion connection between said means, low pressure lubricant from said low pressure pump acting upon said high pressure pump to cause movement thereof and of said second means, at a greater speed than said first means, said lost motion connection permitting such movement, and a check valve between said low and high pressure pumps for opening toward the high pressure one, said 10 check valve being selectively renderable operative or inoperative for high or low pressure delivery respectively.
12. In a lubricant pump structure, low and high pressure pumps, said high pressure pump receiving lubricant from said low pressure pump, a first means for operating said low pressure pump, a second means for operating said high pressure pump through part of a cycle of operation, a pair of controllers, one for each of said 15 means, said controllers being responsive to movement of the first and second means, said low pressure pump being operable to cause completion of the cycle of operation of said high pressure pump, said first and second means being operable by flow of compressed air thereto and therefrom, and snap acting valves for controlling the flow of compressed air to and from said first and second means.
13. In a lubricant pumping structure, low and high pressure pumps, said high pressure pump receiving lubricant from said low pressure pump, a first means for operating said low pressure pump, a second means for operating said high pressure pump through part of a cycle of operation, a pair of controls, one for each of said 20 means, said controls being responsive to movement of the first and second means, said low pressure pump being operable to cause completion of the cycle of operation of said high pressure pump, to cause movement thereof in one direction, compressed air means to cause return movement thereof and a controller for said compressed air means responsive to movement of said high pressure pump.
14. In a lubricant pump structure, low and high pressure pumps, the intake of said high pressure pump being connected with the outlet of said low pressure pump, a first means for operating said low pressure pump, a second means for operating said high pressure pump, a controller for said means, said controller being operable by movement of the second means, an operative but lost motion connection between said means, said low pressure pump being operable to cause movement of said high pressure pump and said second means at a greater speed than it would otherwise be operated by said controller, said lost motion connection permitting such movement, said means being operated, and a relief valve for said low pressure pump, normally retained seated by the compressed air for operating said means.
15. In a lubricant pump structure, a lubricant pump, operating means therefor, means for supplying actuating fluid to said operating means, and a relief valve normally retained seated by said actuating fluid, whereby the pressure of lubricant operable to open said relief valve is in proportion to the pressure of the actuating fluid acting upon the operating means.
16. In a lubricant pump structure, a low pressure high volume pump, a high pressure low volume pump receiving lubricant from said low pressure pump, a first piston for discharging lubricant from said low pressure pump, a second piston for discharging lubricant from said low pressure pump, a fluid pressure and control means therefor responsive to the movement of said first piston for causing the fluid pressure to tend constantly to reciprocate said first piston, the discharge of said low pressure pump being connected with the intake of said high pressure pump so that lubricant from said low pressure pump can act upon said high pressure pump to cause movement of said second piston in one direction, said second piston being movable in the opposite direction by fluid pressure, means for selectively rendering said high pressure pump responsive or non-responsive to said fluid pressure, and a fluid pressure valve for each piston operable by reciprocating movement thereof.
17. In a lubricant pump structure, low and high pressure pumps, said high pressure pump receiving lubricant from said low pressure pump, a first means for operating said low pressure pump, a second means for operating said high pressure pump through part of a cycle of operation, a pair of controllers, one for each of said means, said controllers being operable by movement of the first and second means, said low pressure pump being operable to operate said high pressure pump through the remaining part of said cycle of operation.
18. In a lubricant pump structure, low and high pressure pumps, said high pressure pump receiving lubricant from said low pressure pump, a first means for operating said low pressure pump, a second means for operating said high pressure pump through part of a cycle of operation, a pair of controllers, one for each of said means, said controllers being responsive to movement of the first and second means, said low pressure pump being operable to operate said high pressure pump through the remaining part of said cycle of operation, and selective means to render said second means inoperative.
19. In a lubricant pump structure, a reciprocating high volume pump, a reciprocating low volume pump receiving lubricant therefrom, means for reciprocating said high volume pump comprising a cylinder, a piston reciprocable therein and means responsive to the reciprocations of said piston to control the flow of a fluid pressure to and from said cylinder, the outlet of said high volume pump being connected with the intake of said low volume pump, said high volume pump constituting hydraulic means to reciprocate said low volume pump in one direction and means for reciprocating said low volume pump in the other direction to discharge lubricant at high pressure therefrom comprising a second cylinder, a second piston reciprocable therein and connected with said low volume pump for reciprocation in said one direction thereby and means responsive to the reciprocations of said second piston to control the flow of a fluid pressure to said second cylinder for reciprocating said second piston in said other direction and to control the flow of a fluid pressure from said second cylinder to permit said second piston to be reciprocated in said one direction by said hydraulic means.
20. In a lubricant pump structure, a low pressure high volume pump, a high pressure low volume pump receiving lubricant from said low pressure pump, a first power piston connected with said low pressure pump for discharging lubricant therefrom, a second power piston con-

nected with said high pressure pump for discharging lubricant therefrom, an operative connection between said pistons, whereby each will cause intake of lubricant into the pump of the 5 other piston, actuating fluid acting constantly on said first piston in a low pressure discharging direction and actuating fluid control valve means for admitting actuating fluid to both of said pistons and to exhaust actuating fluid from both 10 of said pistons in response to reciprocations thereof.

21. In a lubricant pump structure, low and high pressure pumps, a first means for operating said low pressure pump in both directions, a second means for operating said high pressure pump in one direction only, the outlet of said low pressure pump being connected with the intake of said high pressure pump, said low pressure pump expelling lubricant into said high 20 pressure pump to cause movement thereof in the opposite direction, said first and second means being air operated and a snap acting valve for controlling the flow of compressed air to and from each of said means, said valves being operable to their opposite positions by movement of said first and second means.

22. In a lubricant pump structure, a low pressure high volume reciprocating pump, a high pressure low volume reciprocating pump, a first power piston for reciprocating said low pressure pump, a second power piston for reciprocating said high pressure pump, the outlet of said low pressure pump being connected with the intake of said high pressure pump, said low pressure pump constituting hydraulic means to move said high pressure pump and said second piston in one direction and to charge said high pressure pump with lubricant, a check valve between said low and high pressure pumps and opening toward the high pressure one, means tending constantly to move said first piston in one direction and actuating fluid valve means for admitting actuating fluid to and exhausting it from one side only of said pistons.

45 23. In a lubricant pump structure, a low pressure high volume reciprocating pump, a high pressure low volume reciprocating pump, a first power piston for reciprocating said low pressure pump, a second power piston for reciprocating said high pressure pump, the outlet of said low pressure pump being connected with the intake of said high pressure pump, a check valve between said low and high pressure pumps and opening toward the high pressure one, means for selectively rendering said check valve operable for high pressure delivery of lubricant from said high pressure pump or inoperative, said high pressure pump, on the discharge stroke thereof, returning lubricant through said check valve 50 when inoperative toward said low pressure pump and actuating fluid valve means for admitting actuating fluid to and exhausting it from said pistons.

65 24. In a lubricant pump structure, a low pressure high volume reciprocating pump, a high pressure low volume reciprocating pump, a first power piston for reciprocating said low pressure pump, a second power piston for reciprocating said high pressure pump, the outlet of said low pressure pump being connected with the intake of said high pressure pump, lubricant pumped from said low pressure pump into said high pressure pump causing movement of said second 70 piston in one direction, a check valve between

said low and high pressure pumps and opening toward the high pressure one, actuating fluid valve means for admitting actuating fluid to and exhausting it from said first piston and for admitting actuating fluid to and exhausting it 5 from said second piston and a control valve for shutting off the actuating fluid to said second piston to thereby render it inoperative and permit low pressure lubricant to pass through said high pressure pump.

10 25. In a lubricant pump structure, a low pressure pump, a high pressure pump, the outlet of said low pressure pump being connected with the intake of said high pressure pump, fluid pressure means for reciprocating said low pressure pump, 15 said high pressure pump including a plunger reciprocated in one direction by low pressure lubricant thereagainst from said low pressure pump, fluid pressure means for reciprocating said high pressure pump in the opposite direction 20 only and a control valve operable to cut off the fluid pressure from said high pressure pump whereupon the low pressure lubricant from said low pressure pump passes through said high pressure pump.

25 26. In a lubricant pump structure, a low pressure pump, a high pressure pump, the outlet of said low pressure pump being connected with the intake of said high pressure pump, fluid pressure means for reciprocating said low pressure pump, 30 said high pressure pump including a plunger reciprocated in one direction by low pressure lubricant thereagainst from said low pressure pump, fluid pressure means for reciprocating said high pressure pump in the opposite direction 35 only and a control valve operable to cut off the fluid pressure from said high pressure pump whereupon the low pressure lubricant from said low pressure pump passes through said high pressure pump, said low pressure lubricant being 40 operable to move said high pressure pump to a position which is non-obstructing to the flow of low pressure lubricant passing through said high pressure pump when said control valve is operable to cut off fluid pressure from said high pressure pump.

45 27. In a lubricant pump structure, a low pressure pump, a high pressure pump, the outlet of said low pressure pump being connected with the intake of said high pressure pump, a discharge 50 hose connected with the outlet of said high pressure pump for discharging either low or high pressure lubricant, fluid pressure means for reciprocating said low pressure pump, said high pressure pump having an expansible chamber, 55 said high pressure pump being reciprocated in one direction by pumping low pressure lubricant thereinto, said low pressure pump being connected therewith to pump low pressure lubricant thereinto, fluid pressure means for reciprocating said high pressure pump in the opposite direction 60 only and a control valve operable to cut off the fluid pressure from said high pressure pump whereupon the low pressure lubricant from said low pressure pump passes through said high 65 pressure pump and is discharged from said discharge hose.

28. In a lubricant pump structure, a low pressure high volume pump, a high pressure low volume pump including a pump plunger, a first power piston connected with said low pressure pump for discharging lubricant therefrom, a second power piston connected with said pump plunger for discharging lubricant therefrom, fluid pressure tending constantly to move said first 70

- piston in one direction, fluid pressure for moving said first piston in the opposite direction, a control valve operated by movement of said first piston to alternately cause introduction of fluid pressure for moving said first piston in said opposite direction and exhaust of fluid pressure for allowing said first piston to move in said first direction, the discharge of said low pressure pump being connected with the intake of said 5 high pressure pump and lubricant from said low pressure pump pressing against said pump plunger to cause movement of said plunger and said second piston in one direction, fluid pressure for moving said second piston in the opposite 10 direction only and means for selectively rendering said high pressure pump responsive or non-responsive to said fluid pressure, said low pressure high volume pump delivering low pressure high volume lubricant when said means renders said 15 high pressure pump non-responsive.
29. In a lubricant pump structure, a low pressure pump, a high pressure pump, a discharge hose connected with the outlet of said high pressure pump, the outlet of said low pressure pump 20 being connected with the intake of said high pressure pump, means for operating said low pressure pump comprising a cylinder, a piston therein, one side of said piston being constantly subjected to fluid pressure, means for alternately 25 admitting and exhausting fluid pressure with respect to the other side of said piston in response to movement of the piston, means for operating said high pressure pump comprising a second cylinder, a second piston therein and means for 30 alternately admitting fluid pressure to the side of said second piston which causes it to move in a direction for discharging lubricant from said high pressure pump and exhausting fluid pressure therefrom in response to movement of said second piston and a valve for cutting off fluid pressure from said second cylinder, lubricant at low 35 pressure from said low pressure pump passing through said high pressure pump and discharging from said nozzle when said valve cuts off fluid pressure from said second cylinder.

the side only of said second piston which causes it to move in a direction for discharging lubricant from said high pressure pump and exhausting fluid pressure therefrom in response to movement of said second piston, lubricant from said low pressure pump moving said high pressure pump in the opposite direction when said last means exhausts fluid pressure from said second piston. 5

30. In a lubricant pump structure, a low pressure pump, a high pressure pump, a discharge hose connected with the outlet of said high pressure pump, the outlet of said low pressure pump being connected with the intake of said high pressure pump, means for operating said low pressure pump comprising a cylinder, a piston therein, one side of said piston being constantly subjected to fluid pressure, means for alternately admitting and exhausting fluid pressure with respect to the other side of said piston in response to movement of the piston, means for operating said high pressure pump comprising a second cylinder, a second piston therein and means for alternately admitting fluid pressure to the side of said second piston which causes it to move in a direction for discharging lubricant from said high pressure pump and exhausting fluid pressure therefrom in response to movement of said second piston and a valve for cutting off fluid pressure from said second cylinder, lubricant at low pressure from said low pressure pump passing through said high pressure pump and discharging from said nozzle when said valve cuts off fluid pressure from said second cylinder. 20 25 30
